UNITED STATES PATENT OFFICE.

GEORGE H. HUENERGARDT, OF COLLEGEVIEW, NEBRASKA.

WASHING-MACHINE.

1,099,048.

Specification of Letters Patent.

Patented June 2, 1914.

Application filed December 18, 1912. Serial No. 737,524.

To all whom it may concern:

Be it known that I, GEORGE H. HUENERGARDT, a subject of the Czar of Russia, residing at Collegeview, in the county of Lancaster and State of Nebraska, have invented a new and useful Washing-Machine, of which the following is a specification.

This invention relates to washing machines of that type utilizing tubs mounted for oscillation, one of the objects of the present invention being to provide novel means whereby the tub can be held against movement while in either an upright or an inverted position, the locking means being simple in construction and readily accessible for engaging and releasing the tub.

Another object is to improve generally upon the construction of devices of this character.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—Figure 1 is a front elevation of a washing machine having the present improvements combined therewith, portions of the supporting legs being broken away. Fig. 2 is a transverse section through one side portion of the tub and showing the locking means partly in section and partly in elevation. Fig. 3 is an enlarged detail view of one of the side fastenings constituting one of the locking members. Fig. 4 is a perspective view of the other locking member.

Referring to the figures by characters of reference 1 designates upwardly converging legs preferably formed of angle strips secured, at their upper ends, to a substantially triangular block 2 having an integral boss 3 which is bored longitudinally. Formed upon the upper end of the block 2 are ears 4 having a tongue 5 pivotally mounted therebetween, as shown at 6, this tongue being adapted to normally bear upon the top of the block 2 so as to thus extend inwardly at right angles to the sides of the tub hereinafter described.

The bore in the boss 3 is adapted to receive a trunnion 7 extending from a plate 8 which is elongated, as shown particularly in Figs. 1 and 3 and has its ends forked, as shown at 9 and 10. The fork 9 is provided with ribs 11 which converge toward the trunnion 7 so as to form a longitudinal channel 12. A short arm 13 extends radially from that portion of the plate 8 carrying the trunnion 7 and this arm has a longitudinal channel 14. Said arm is preferably disposed at about 160 degrees to the channel 12.

Plate 8 is attached to one side of a substantially semi-cylindrical tub 15, the fastening means being extended through openings 16 in the terminals of the forks and also through openings 17 formed in the plate adjacent the trunnion 7. A plate similar to the plate 8 may be employed for supporting the far side of the tub 15, although it is to be understood that said plate constitutes no part of the present invention and need not be provided with the arm 13 or the channel 12.

A cross brace 18 connects the legs 1 and has outstanding terminal portions 19 to which are connected the lower ends of downwardly diverging coiled springs 20. The upper ends of these springs are connected to the lower ends of downwardly diverging arms 21 extending from a collar 22 which is secured to the trunnion 7 by means of a set screw 23 or the like. A socket member 24 extends upwardly from the collar 22 and is adapted to receive a handle 25.

It is to be understood that when the tongue 5 is extended outwardly from between the ears 4, the trunnion 7 can be rotated back and forth by means of the handle 25, springs 20 thus being placed successively under stress. During this movement of the socket member, trunnion 7 rotates within the boss 3 and the tub 15 swings back and forth. Should it be desired to lock the tub against movement, as when a wringer is to be attached thereto, the tongue 5 is swung inwardly so that its inner end will become seated within the channel 12. Should it be desired to lock the tub in an inverted position so that it can drain readily and will shed rain and the like which may be precipitated thereon, the tub is inverted so as to bring the channeled arm 13 opposite the tongue 5 whereupon said tongue is swung inwardly so as to become seated in the channel 14.

What is claimed is:—

The combination with a supporting structure, a tub mounted for oscillation, a plate having radial grooves and connected to the tub, and a trunnion extending from the plate, of a block secured to the supporting structure and constituting a bearing for the trunnion, spaced ears extending from the block, there being an integral connection between the lower portions of the ears, and a flat plate forming a locking tongue pivotally mounted between the ears and normally bearing upon said connection and extending

into one of the grooves, said tongue having its broad faces in planes perpendicular to its axis of movement and being shiftable out of normal position to release the plate all portions of the plate being directly above the trunnion.

In testimony that I claim the foregoing as my own, I have hereto affixed my signature in the presence of two witnesses.

GEORGE H. HUENERGARDT.
